INVENTOR:
VINCENT C. DE YBARRONDO,

BY *Ferd. Flannery*
ATTORNEY.

Patented May 17, 1927.

UNITED STATES PATENT OFFICE.

VINCENT C. DE YBARRONDO, OF LOS ANGELES, CALIFORNIA.

PNEUMATIC PULLEY FOR MOTION-PICTURE FILMS.

Application filed June 30, 1926. Serial No. 119,525.

My invention relates to pulleys and more particularly to a pneumatic pulley.

In preparing motion picture film commercially the negative must be developed, fixed, washed and dried. A positive is then printed from the negative and the positive must be developed, fixed, washed and dried.

Various machines have been devised for passing the film through these preparing processes. After the positive film is prepared it must be run through a projecting machine to produce a moving picture. The picture produced may be greatly marred by any scratches upon a surface of the negative film, which are transmitted to the positive in printing, or by scratches made upon a surface of the positive film directly.

It has been found that pulleys over which the film must pass in the preparing and projecting machines cause such scratches upon the film.

It is a broad object of my invention to provide a pulley for use in handling motion picture film which will not scratch the surface of the film.

The pulley of my invention is designed to be used either as a drive pulley or as an idle pulley. Openings are provided in the film contacting surface of the pulley from which air may be drawn through the axle of the pulley. When the film lies over the mouth of these openings a vacuum is thus created in the openings which holds the film against the pulley and prevents any slipping of the film relative thereto.

It is therefore another object of my invention to provide a pneumatic pulley which utilizes a vacuum to draw a film into non-slipping relation with said pulley.

If it is desired to pass the film idly over the pulley, air is blown outwardly from the axle through the aforementioned openings thus creating a cushioning layer of air between the pulley and the film.

A still further object of my invention is to provide a pneumatic pulley in which an air cushion is formed between the pulley and a moving picture film passing over it so that the surface of the film does not contact the pulley.

Yet another object of my invention is to provide a pneumatic pulley in which a vacuum formed to grip a moving picture film thereto is broken when it is desired that said film be disengaged by said pulley.

Further objects and advantages will be made evident hereinafter.

Fig. 1 is a side elevational view of a preferred embodiment of my invention.

Fig. 2 is a vertical sectional view taken medially and longitudinally through the pulley of my invention.

Fig. 3 is a vertical sectional view taken on the line 3—3 of Fig. 2.

Fig. 4 is a fragmentary vertical sectional view of a modified form of my invention.

A pneumatic pulley 10 has a pulley wheel 11 which is shown as provided with end flanges 12. The wheel 11 has a cylindrical peripheral surface 13 and an axial bearing 70 opening 14. Connecting the opening 14 with the surface 13 are radial openings 15. A neck 16 projects from one end of the pulley wheel 11 and threadedly receives a driving pulley 17 which is adapted to receive a belt (not shown) for the purpose of imparting a rotary movement to the pulley wheel 11.

An axle 20 fits neatly within the bearing opening 14 of the pulley wheel 11 so that the latter may rotate readily thereon. A central passageway 21 is formed throughout the length of the axle 20, one end of the passageway 21 being closed by a plug 22 threadedly received therein. The plug 22 has a knurled head 23 for a purpose which will be described later. The axle 20 has ports 28 formed therein so that as the pulley wheel 11 is rotated upon the axle 20 the radial openings 15 will come into registry with the ports 28 over a certain angular portion of the rotation of the pulley wheel 11. Channels 30 are formed in the outer surface of the axle 20 as shown in Figs. 3 and 4, for a purpose which will be described later.

A support 35 has an opening 36 in which an end of the axle 20 is adapted to be snugly received. A thumb screw 38 is threadedly received in a suitable aperture formed in the support 35 and is adapted to be screwed down against the axle 20 to retain the same in a given position in the opening 36. A passage 40 is formed in the support 35 which communicates with a nipple 41 threadedly received at 42 in the lower end of the support 35 and which is connected by a union 43 to a pressure or exhaust line 44. The pressure or exhaust line 44 is connected to the pressure or exhaust end of a suitable fluid pump (not shown). The support 35

may be secured in any manner so as to hold the pulley wheel 11 in a suitable position for use.

In Fig. 4 a pulley wheel 50 is shown which 5 is identical to the pulley wheel 11 excepting that an outer cylindrical surface 52 thereof is provided with sprocket teeth 53. These sprocket teeth 53 are spaced at equal angles radially around the surface 52 so as to penetrate the holes provided at the edges of a strip of film which is passed over the surface 52 of the pulley wheel 50.

The operation of my invention is as follows:

15 When it is desired to use the pulley wheel 11 as a drive pulley, means, such as a belt placed upon the driving pulley 17, are used for rotating the pulley wheel 11. A motion picture film 60, as shown by dotted 20 lines in Fig. 3, is now passed around the pulley wheel 11, as shown. The pipe 44 is connected to the exhaust end of a fluid pump and a 25 vacuum is drawn upon the passage 21 of the axle 20. The outer mouths of those of the radial openings 15 which are now in communication with the ports 28 are closed by contact of the film 60 with the outer surface 13 of the pulley wheel 11. The vacuum in the passageway 21 is therefore communicated through the ports 28 to this group of the radial openings 15. The 30 vacuum in this group of radial openings 15 draws the film 60 closely against the outer surface of the pulley wheel 11 and, as the latter rotates, causes the film to be moved with the surface 13 and prevents any sliding action of the film 60 relative to the surface 13. As the wheel 11 rotates the group of openings 15 upon which a vacuum 35 has been drawn pass successively out of registry with the ports 28 so that they no longer communicate through the ports 28 with the passage 21.

40 As the openings 15 are thus shut off from communication with the passageway 21 they come into communication with channels 30 which communicate with a lower radial opening 15, the mouth of which is open so that air is admitted through such lower opening to relieve the vacuum in each opening 15 as it moves into communication with a channel 30. As the vacuum is thus relieved in the openings 15 they release their grip upon the film 60 which continues in its 45 prescribed path away from the pulley wheel 11. It will be noted that the channels 30 are formed in the outer surface of the axle 20 adjacent to each of the opposite ends of the ports 28. Thus the pulley wheel 11 may 50 be rotated in either direction and the vacuum formed in the radial openings 15 will be relieved as just described.

In case it is desired to extend the film 60 to and from the pulley wheel 11 at a 55 different angle than that shown in Fig. 3,

the thumb screw 38 may be released from contact with the axle 20 and the axle 20 may be rotated by manually engaging the knurled head 23 so that ports 28 will be disposed opposite the area of the peripheral surface 13 which will be contacted by the film 60. The thumb screw 38 may then be reset to secure the axle 20 in this position. The pulley will now operate in exactly the same manner described excepting that the gripping area will be disposed at a different position about the axis of the pulley.

When it is desired to use the pulley wheel 11 as an idle pulley the pipe 44 is connected to the exhaust end of a fluid pump and a 80 fluid, preferably air, is pumped under pressure into the passage 21 of the axle 20. This air under pressure escapes through the ports 28 and is conducted through the radial openings 15 to the peripheral surface 13. The film 60 is here placed about the pulley wheel 11 in the same manner as is shown in Fig. 3 but passes over the pulley wheel 11 without coming in contact with the peripheral surface 13. This is due to the escaping of air 90 from the openings 15 so as to form an air cushion between the film 60 and the peripheral surface 13. This protects the film 60 from any chance of being scratched by contact with the pulley wheel 11.

In Fig. 4 the pulley wheel 50 is provided with sprocket teeth 53 which are adapted to engage with the holes usually provided along the edges of a motion picture film, otherwise the wheel 50 is similar in construction to the pulley wheel 11 and either the vacuum gripping action or the air cushion action may be set up between the pulley 50 and the film 60. The teeth 53, however, provide a means for engaging the film so that the pulley 50 may be used as a drive pulley and since the vacuum gripping action will thus be unnecessary, an air cushion may be set up between the film 60 and the surface 52 of the pulley wheel 50 for the purpose of preventing any scratching of the surface of the film 60 by contact with the surface 52 of the pulley 50.

It is contemplated to make special use of the pneumatic pulley 10 in the drier of a 115 motion picture film developing machine. Here warm air is passed outwardly through the pulley wheel 11, this air not only causing the film 60 to ride easily over the pulley but acting upon the film as a drying 120 agent. Moreover, when it is desired to treat the film when drying with any chemical, this chemical in the form of a vapor may be dissolved in the air passed outwardly through the pulley wheel 11 and thus be 125 brought against the film by the streams of air issuing from the radial openings 15.

I claim as my invention:

1. In combination: a pulley wheel having a peripheral surface in which openings 130

- are formed; means for forming a vacuum in one of said openings when its mouth is covered; and means for connecting an uncovered opening with said covered opening for releasing said vacuum before said mouth is uncovered. 5
2. In combination: a pulley wheel having a peripheral surface in which openings are formed; an axle upon which said wheel may turn; there being a passage in said axle; means for extracting the air from said passageway to form a vacuum in one of said openings when its mouth is covered; and means for releasing said vacuum before said mouth is uncovered. 10
3. In combination: a pulley wheel having a peripheral surface in which openings are formed; an axle upon which said wheel may turn, there being a passage in said axle and a port connecting said passage with one of said openings when said opening is disposed within a certain range of its possible radial positions; and means for imposing a vacuum upon said passage which will be communicated through said port to said opening when the outer mouth of said opening is closed. 20
4. In combination: a pulley wheel having a peripheral surface in which openings are formed; and means for forcing a fluid from said openings to form a fluid cushion between said wheel and a flexible member guided in direction by said wheel. 30
5. In combination: a pulley wheel having a peripheral surface in which openings are formed; an axle upon which said wheel may turn, there being a passage in said axle and a port connecting said passage with one of said openings when said opening is disposed within a certain range of its possible radial positions; means for supporting said 35
- axle; means for rotatably adjusting said axle; and means for imposing a vacuum upon said passage which will be communicated through said port to said opening when the outer mouth of said opening is closed. 45
6. In combination: an axle having a passage formed in the interior thereof and a port connecting said passage with the bearing surface of said axle; a pulley wheel adapted to be rotatably supported upon said axle, and having openings connecting the bearing surface of said pulley with the periphery thereof; and means for extracting the air from said passageway to form a vacuum in said openings when these are in registry with said port and when the outer mouths thereof are closed, there being means for breaking said vacuum in said covered openings by connecting these with uncovered 50 55
- openings. 60
7. In combination: an axle having a passage formed in the interior thereof and a port connecting said passage with the bearing surface of said axle; a pulley wheel adapted to be rotatably supported upon said axle, and having openings connecting the bearing surface of said pulley with the periphery thereof; and means for extracting the air from said passageway to form a vacuum in said openings when these are in registry with said port and when the outer mouths thereof are closed, there being a port formed in the bearing surface of said axle for breaking said vacuum in said covered 65 70 75
- openings by connecting these with uncovered openings. 70

In testimony whereof, I have hereunto set my hand at Los Angeles, California, this 24th day of June, 1926.

VINCENT C. DE YBARRONDO.
